UNITED STATES PATENT OFFICE.

BENJAMIN VAN VRANKEN, OF SCHENECTADY, NEW YORK.

FLUSH-TANK AND SIPHON.

SPECIFICATION forming part of Letters Patent No. 340,836, dated April 27, 1896.

Application filed December 26, 1895. Serial No. 186,685. (No model.)

To all whom it may concern:

Be it known that I, BENJAMIN VAN VRANKEN, a citizen of the United States, residing at Schenectady, in the county of Schenectady and State of New York, have invented certain new and useful Improvements in Flush-Tank Siphons; and I do hereby declare the following to be a full, clear, and exact description of the invention, such as will enable others skilled in the art to which it appertains to make and use the same.

My invention relates to certain new and useful improvements in flush-tank siphons, and is designed to furnish a device which shall be 15 of simple and economical construction, thoroughly effective in operation under the varying conditions of its use, and which will obviate the necessity, met with in prior apparatus having analogous functions, of frequent repair. For the attainment of these ends I have 20 devised the construction illustrated in the accompanying drawings, wherein—

Figure 1 represents a side elevation, partly broken away, of one form of my invention. Fig. 2 represents a plan view of the same, the 25 top of the siphon-tank being removed to better illustrate the disposition of parts. Fig. 3 represents a vertical cross-section through the siphon-tank and tip-basin, the siphon-pipe being shown in elevation; and Fig. 4 represents 30 a side elevation, partly broken away, of a modification of the device shown in the preceding figures.

Similar letters of reference indicate similar 35 parts throughout the several views.

In the form illustrated in the first three figures of the drawings, A indicates a tank, preferably of iron or of brick-work, and adapted to be contained within a larger cistern having 40 the desired capacity required for the flushing operation. The tank A is inclosed upon all sides, and contains the longer arm, B', of a siphon, the shorter arm, B, of which is contained within the outer cistern. Upon its 45 lower end the arm B' is provided with pivot pins or lugs b, and upon the pins or lugs is suspended the tip-basin C. The said tip-basin is provided with serrated or toothed interior side lugs, c, upon which the basin is hung. 50 Set-screws d' upon cross-pieces d, located at opposite sides of the arm B' and upon the tip-

basin, determine the extent of movement or play of the latter, and may be adjusted as desired, so as to permit of a greater or less inclination of the basin when tipped. E represents the exit-pipe from the siphon tank.

In Fig. 4 is represented a smaller tank, A', leading into a sewer-pipe, F. The siphon-arm B' is leaded or cemented at its entrance into the tank. The construction of the tip-basin and its means of attachment and adjustment are identical with that above described, and need not, therefore, be recapitulated.

The operation of my invention is as follows: The water contained within the tip-basin seals 65 the mouth of the longer arm, B', of the siphon. As the water rises, therefore, in the outer cistern or space surrounding the siphon-tank and attains the level of the mouth of the shorter arm, B, it begins to compress the body of air 70 within the siphon-pipe. As the water continues to rise, entering the short arm B, the compression of the imprisoned air within the siphon-pipe increases, and its pressure being greater than that of the atmosphere it results 75 that the height of the water in the cistern continually exceeds the height of the water in said short arm. When the water in the short arm reaches the level of the bend of the pipe, therefore, the main body of water 80 is at a higher level, as shown by the broken lines, Figs. 1 and 4. At this period the water slowly trickles over into the longer arm, B', and entering the basin C tips it, suddenly releasing the compressed air, whereupon the 85 water rises instantly in the short arm B to the level of the surrounding water, and, no longer retarded by the compressed air, pours down the longer arm, B', in full volume, thereby establishing the siphonage and emptying the 90 cistern.

It will be readily seen that by the use of my device a very small amount of water entering the tip-basin suffices to set the siphon in operation. This is an important consideration in 95 sewer-tanks, which ordinarily are fed by a very small stream. Siphons closed at their ends by valves have been found practically useless in such cases. Thus, where such valves become worn, or obstructed so as to admit air, 100 the water entering the siphon will often escape as fast as it is admitted into the tank; or

if the valve should for a time remain tight, which is a condition almost impossible to secure, the water, as it slowly enters the long arm, will just relieve the valve slightly, and run out without starting the siphonage. Such valves, moreover, are in constant need of repair, and, by reason of the accuracy with which they must fit the end of the pipe, are difficult and costly to manufacture. The tip-basin obviates all of these defects, requiring no accurate adjustment or frequent repair, and is absolutely certain in its operation whatever the flow into main cisterns.

While I prefer the means illustrated for suspending the tip-basin and adjusting the same, it is evident that others may be substituted in their stead, accomplishing the same result. I do not wish, therefore, to be understood as restricting myself to these particular means, but contemplate in some instances using such others as are recognized as their mechanical equivalents.

Having thus described my invention, what I claim, and desire to secure by Letters Patent, is—

1. A siphon provided at the extremity of its longer arm, with a tip-basin, substantially as described.

2. A flushing device for sewers and the like, consisting of a tank having an exit-opening adapted to connect with the sewer-pipe, a siphon-pipe having its longer arm within the tank and its shorter arm outside of the same, and a tip-basin below the longer arm of said siphon, substantially as described.

In testimony whereof I affix my signature in presence of two witnesses.

BENJAMIN VAN VRANKEN.
